UNITED STATES PATENT OFFICE

124,207

DESIGN FOR A CIRCUS GAME BOARD

Joseph Setz, Hillside, N. J.

Application August 28, 1940, Serial No. 94,685

Term of patent 3½ years

To all whom it may concern:

Be it known that I, Joseph Setz, a citizen of the United States, residing at Hillside, in the county of Union and State of New Jersey, have invented a new, original, and ornamental Design for a Circus Game Board, of which the following is a specification, reference being had to the accompanying drawing, forming part thereof.

The characteristic features of my design reside in the figures representing circus performers on vari-colored fields.

In the drawing the figure is a plan view of a circus game board, showing my new design. The article is of no appreciable or substantial thickness.

I claim:

The ornamental design for a circus game board, as shown and described.

JOSEPH SETZ.
